CLAIM

The ornamental design for a pool lamp, as shown and described.

DESCRIPTION

FIG. 1 is a top perspective view of a pool lamp design showing my new design.

FIG. 2 is a front view of a pool lamp.

FIG. 3 is a rear view of a pool lamp.

FIG. 4 is a left side view of a pool lamp.

FIG. 5 is a right side view of a pool lamp.

FIG. 6 is a top view of a pool lamp.

FIG. 7 is a bottom view of a pool lamp.

FIG. 8 is a bottom perspective view of a pool lamp; and, FIG. 9 is a front perspective view of a pool lamp design showing the separated state of base and main body.

The broken lines in the drawings depict portions of the pool lamp that form no part of the claimed design.
